INTERNAL-COMBUSTION ENGINE

Marsden Ware, Huntington Woods, Mich., assignor to Packard Motor Car Company, Detroit, Mich., a corporation of Michigan

Application February 26, 1940, Serial No. 320,798

4 Claims. (Cl. 123—171)

1

This invention relates to engines and more particularly to engines of the fuel injection type.

Fuel injectors are usually arranged to extend through a wall of engine cylinders in order that the fuel can be sprayed into air charges in the combustion chambers. Heat, resulting from compression of the air charges in the cylinders and from combustion, will cause the injectors and their securing means to expand even though a cooling system is employed. The injector is usually clamped tightly against a cylinder wall and temperature changes act to loosen the engagement of the injector with the cylinder wall due to differences in the coefficient of expansion of the injectors and their securing means. When the injectors become loose there will be leakage from the cylinders thus reducing compression pressure and allowing escape of at least a portion of the fuel and air charges.

An object of the invention is to improve the operation of engines by providing an air system for efficiently cooling fuel injectors, their securing means and the heads of the cylinders with which they are associated.

A further object of the invention is to improve the operation of an injection type of engine by the provision of deflector means for directing air in streams over the major portion of the cylinder heads and the injectors secured thereto.

Other objects of the invention will appear from the following description taken in connection with the drawings, which form a part of the specification, and in which:

Fig. 1 is a top plan view of one cylinder of an engine with the cowling ring removed;

Fig. 2 is a sectional view taken on line 2—2 of Fig. 3;

Fig. 3 is a sectional view of the cylinder and air deflector structure taken on line 3—3 of Fig. 2;

Fig. 4 is an elevational view of the head end of a cylinder having a modified form of air deflector means;

Fig. 5 is a plan view of the modified form of the invention shown in Fig. 4;

Fig. 6 is a sectional view taken on line 6—6 of Fig. 5;

Fig. 7 is another sectional view taken on line 7—7 of Fig. 5.

The invention is shown associated with one cylinder of an engine having a cylinder block 10 terminating in a flanged end 9 on which a head structure 11 is seated. In Figs. 1 to 3 inclusive, this cylinder head structure is cast as an integral unit and in Figs. 4 to 7, inclusive, the cylinder head is a sectional structure comprising a central

2

portion formed of material such as aluminum and a ring 8 formed of steel or similar material that is threaded interiorly and screwed upon the inner section. The provision of a steel ring reinforces the head structure so that it is capable of withstanding greater loads than when the structure is formed entirely of aluminum. The head structure in both forms of the invention is secured to the cylinder flange 9 by means of studs 12 screwed into the cylinder flange and nuts 9' that are screwed on the outer ends of studs. The head structure and cylinder shown in Figs. 1 to 3, inclusive, are each provided with a plurality of circumferential cooling fins 13 and similar fins can be provided on the cylinder shown in Figs. 4 to 7, inclusive, if desired. A conventional piston 14 is arranged in the usual manner within the cylinder and has a depressed end that cooperates with the end of the cylinder head to form a combustion chamber 15.

An opening 16 extends through the central portion of the head wall and is similar in form to the outlet end of a fuel injector 17 that extends therethrough. The opening has a conical wall portion 18 against which the injector shoulder 19 seats and seals. The head wall is also formed with a central well 20 through which the nozzle extends, and a pair of bosses 21 projects from the head wall at the bottom of the well a desired distance into the well and is oppositely disposed adjacent the injector. The injector is formed with a pair of apertured flanges 22 arranged to align with the bosses in the well. The apertures in the flanges receive studs 23 which are suitably anchored in the bosses and nuts 24 are applied to the studs to tightly clamp the injector shoulders 19 against the seat 18 in the head wall. The studs are formed of material that will compensate for difference in expansion caused by temperature differences of the studs and injectors, and in the present instance they have substantially the same coefficient of expansion as the injector. As the studs are parallel with the injector in an axial direction, axial expansion and contraction of the securing means and the injector will be compensated for under all engine heat conditions so that a tight fit of the injector against the head wall seat is maintained.

The major portion of the injector lies within the engine head well in order to reduce the overall diameter of the engine taken axially through cylinders, and some form of cooling system for the injector portion within the well is desirable to lower the injector temperature and the head structure temperature under engine operating

conditions. In the illustrated forms of the invention, deflector means is associated with the head structure to direct streams of air into and through the well. In this connection a plurality of radially extending fins 25 are thermally associated with the outer face of the end wall of the head structure. In Figs. 1 to 3 inclusive, these fins are cast integral with the head structure while with the cylinder shown in Figs. 4 to 7 the fins are formed of sheet metal and are fixed in grooves formed in the central section of the head structure. In Fig. 3 the fins extend from adjacent the injector to the periphery of the cylinder head but terminate in the well a desired distance above the bottom thereof. In the form of cylinder shown in Figs. 1 to 3, inclusive, the fins are of varying length in a radial direction and some of them are formed with curved ends as indicated at 26, the curved portions extending in directions to act as scoops for guiding air into the well. Semi-circular fins 27 project from the bottom of the well in a direction fore and aft of the engine and beneath the lower extremity of the portions of the fins 25 projecting into the well. In the modified form of the invention the fins 25 are associated only with the inner section of the head and terminate short of the applied ring 8.

The deflector means is associated with the cylinder head and fins 25 in a relation to provide paths through which air must flow into and out of the well to absorb heat from the head structure, the injector and the injector securing means. This deflector means, as shown in Fig. 3, is in the form of a sheet metal collar or funnel 28 formed to surround the upper portion of the injector 17 and similar in shape to the upper inner terminals of the fins 25. This funnel is seated against the fins and projects a short distance into the well so that air will be deflected between the front fins, into the forward portion of the well, across the well and then out of the well from between the rear fins. In other words, this funnel 28 forms a closure for the top and a portion of the inner terminals of the fins that will deflect the air therebeneath into the forward part of the well and out of the rear portion of the well. The fins 27 are arranged in fore and aft direction to assist in guiding the air from the front to the rear of the well and they also serve as cooling means for the head wall. The portion of the nozzle in the well beneath the collar 28 can be provided with suitable cooling fins 29 in the path of air travel. These fins as shown in Fig. 3 extend radially while in Fig. 6 they extend axially of the injector. A gasket 30 is arranged between the outer flanged end 31 of the collar and engine cowl 32 and suitable means can be utilized to removably secure the collar and cowl together. With this form of the invention, air will flow across the head structure in streams defined by the two fins, the collar and the cylinder head structure.

In the form of the invention shown in Figs. 4 to 7, inclusive, a collar member 28, similar generally to that just referred to, is employed but it projects further into the well and is considerably spaced from the injector. In this instance the collar member fits against inner and upper edge portions of the fins 25 but continues outwardly of the well to the outer edge of the head where it is anchored on the studs 12 and rests on nuts 9. Spacer elements 33 are arranged between the nuts 9' and the collar and the collar is secured by nuts 33' threaded on the ends of the studs. A forward half of this collar has an extension shield 34 that projects outwardly from the cylinder head

and is bent downwardly and inwardly to prevent air from moving into the well through the space between the collar and the top of the cylinder head structure and to also provide a collecting means for air entering the well and a guiding means for air leaving the well. Fitted over the collar member 28 and secured in such relation by the studs 12 and 33' is a cover member 35 that encloses the injector and guides air downwardly through the collar member from which it passes into the bottom of the well. The cover rests on spacers 34' that are seated on the funnel and telescope the studs 12. The rear section of this cover is closed upon the funnel while the forward portion of the cover has an extension 36 that flares upwardly and forms a mouth 37 for the cooling air. This flared mouth portion of the cover overlies the extension closure portion 34 of the funnel.

The direction of air flow into and out of the well is shown by arrows in Figs. 5 and 6 of the drawings. Air enters the space between the funnel and cover through the forwardly extending mouth 37 and it passes down through the funnel, absorbing heat from the nozzle and the securing means, and into the bottom of the well from which it flows in streams through paths formed by the fins 25, the funnel 28 and the wall forming the well. Air in travelling out of the well passes rearwardly into the funnel 28 and into the well from which it flows outwardly through the open ends of the shield 34 or through the space between the funnel and the cylinder head.

In both forms of the invention air circulation through the well in the head of the cylinder is controlled in the direction of its flow and will absorb heat from the injector, the injector securing means and the head of the cylinder. In this manner temperature is reduced during operation of the engine so that the engine efficiency is thereby improved. The injector securing means is such that a tight joint between the injector and the cylinder head will be maintained under all engine operating conditions.

Although the invention has been described in connection with a specific embodiment, the principles involved are susceptible of numerous other applications which will readily occur to persons skilled in the art. The invention is therefore to be limited only as indicated by the scope of the appended claims.

What is claimed is:

1. In an engine, a cylinder head having a well extending inwardly thereof in an axial direction, a plurality of fins extending radially in the well and fixed to the head, said fins projecting outwardly of the well beyond the outer wall of the head, a collar projecting part way into the well and contacting the inner edges of the fins, said collar having a flared outer end seated against the edges of the fins projecting beyond the head, the forward portion of the flared outer end of the collar extending beyond the periphery of the head and bent downwardly below the portions of the fins projecting beyond the cylinder head, a fuel injection nozzle fixed in the well and projecting into and in spaced relation with the collar, and a cover enclosing the flared end of the collar, said cover having a forward portion spaced above the collar to form an air inlet mouth therebetween.

2. In an engine, a cylinder head having a well extending inwardly thereof in an axial direction, a plurality of radially extending fins in the well fixed to the head, said fins projecting outwardly

of the well beyond the outer wall of the head, a collar projecting part way into the well and contacting the inner edges of the fins, said collar having a flared outer end seated against the edges of the fins projecting beyond the head, the forward portion of the flared collar end being extended downwardly beyond the end of the cylinder head to shield the space rearwardly thereof, a fuel injection nozzle fixed in the well and projecting into and in spaced relation with the collar, and a cover on the flared end of the collar having a portion forming an air inlet mouth at its forward end through which air passes into the collar.

3. In an engine, a cylinder head having a well extending inwardly thereof in an axial direction, a plurality of radially extending fins in the well fixed to the head, said fins projecting outwardly of the well beyond the outer wall of the head, the forward portion of the flared collar end extending downwardly beyond the end of the cylinder head to shield the space rearwardly thereof from the entrance of outside air, a collar projecting part way into the well and contacting the inner edges of the fins, said collar having a flared outer end seated against the edges of the fins projecting beyond the head, a fuel injection nozzle fixed

5

in the well and projecting into and in spaced relation with the collar, and a cover enclosing the rear portion of the end of the collar and having a mouth above the forward portion of the collar through which outside air flows to the interior of the collar.

10

4. In an engine, a cylinder head having a well extending inwardly thereof in an axial direction, a plurality of radially extending fins in the well fixed to the head, said fins projecting outwardly of the well beyond the outer end wall of the head, a sheet metal collar projecting part way into the well and contacting the inner edges of the fins, said collar having the outer end flared and seated against the edges of the fins projecting beyond the head, the forward half of said flared end of the collar extending beyond the cylinder head and bent downwardly to shield the space rearwardly thereof to prevent the entry of outside air into such space, a fuel injection nozzle fixed in the well and projecting into and in spaced relation with the collar, and a cover fixed over the collar having the forward portion thereof spaced above the collar to form an inlet mouth through which air passes into the interior of the collar.
